Primary Examiner — Mark Goodwin(74) *Attorney, Agent, or Firm* — Masuvalley & Partners(57) **CLAIM**

The ornamental design for a portion of mower, as shown and described.

DESCRIPTION

FIG. 1 is a perspective view of the portion of mower according to the invention;

FIG. 2 is another perspective view of the portion of mower of FIG. 1;

FIG. 3 is a front elevation view of the portion of mower of FIG. 1;

FIG. 4 is a rear elevation view of the portion of mower of FIG. 1;

FIG. 5 is a left side elevation view of the portion of mower of FIG. 1;

FIG. 6 is a right side elevation view of the portion of mower of FIG. 1; and,

FIG. 7 is a top plan view of the portion of mower of FIG. 1. The broken line disclosure, as well as line shading in parts of the drawings are included for the purpose of illustrating use and environment and form no part of the claimed design.
